UNITED STATES PATENT OFFICE.

DE WATT PEPPER, OF NEW MILFORD, CONNECTICUT.

DESIGN FOR A DIVAN-FRAME.

SPECIFICATION forming part of Design No. 36,199, dated January 27, 1903.

Application filed December 26, 1902. Serial No. 136,744. Term of patent 3½ years.

To all whom it may concern:

Be it known that I, DE WATT PEPPER, a citizen of the United States, residing at New Milford, in the county of Litchfield and State of Connecticut, have invented and produced a new, original, and ornamental Design for a Divan-Frame; and I do hereby declare the following to be a full, clear, and exact description of the invention, such as will enable others skilled in the art to which it appertains to make and use the same.

The accompanying drawing illustrates a front elevation of my new design.

As shown in the drawing, the leading or material features of my design are the plain generally sloping sides 1, which at their outer front extremities rest upon columns the tops of which represent dog-like heads 2 with open mouths, the bottom portions of said columns

having fluted parts 3, which surmount toe-like portions 4, while the intermediate or body portions 5 of said columns are bounded by compound curves that are intersected by beaded portions 6. The surface of the front rail 7 of the divan, which supports the seat 25 thereof, extends between said columns and is left perfectly plain.

Having thus described my invention, what I claim as new, and desire to secure by Letters Patent, is—

The ornamental design for a divan-frame, as herein shown and described.

In testimony whereof I affix my signature in presence of two witnesses.

DE WATT PEPPER.

Witnesses:

FREDERICK A. PICKETT,
JAMES H. McMAHON.
